Primary Examiner — Ian Simmons*Assistant Examiner* — Carissa C Fitts*(74) Attorney, Agent, or Firm* — Studebaker & Brackett PC(57) **CLAIM**

We claim the ornamental design for a lancet holder, as shown and described.

DESCRIPTION

FIG. 1 is a perspective view of a lancet holder according to my design;

FIG. 2 is a front view of the same;

FIG. 3 is a rear view of the same;

FIG. 4 is a left side view of the same;

FIG. 5 is a right side view of the same;

FIG. 6 is a top plan view of the same; and,

FIG. 7 is a bottom view of the same.

The broken lines showing a lancet head and operating elements in FIGS. 1-7 are for illustrative purposes only and form no part of the claimed design.
